METHOD OF AND APPARATUS FOR
PRINTING AND DYEINGAlfred B. Pöschel, Brooklyn, N. Y., assignor to
Decorative Development, Inc., Brooklyn, N. Y.,
a corporation of Delaware

Application November 29, 1932, Serial No. 644,831

11 Claims. (Cl. 41—33)

This invention relates to the art of printing and dyeing of absorbent materials by transfer; more particularly it deals with improvements in the manufacture of dye transfer sheets and with improvements in the apparatus for and method of transferring or applying the dyes from such a transfer sheet to fabrics such as silk, rayon, celanese, velvet, cotton, etc.

It is well known that half-tone color printing on paper provides more accurate reproductions of the original designs than is possible by direct printing on fabrics. Previous attempts, however, to manufacture dye transfer sheets for the purpose of printing and dyeing multi-colored designs on fabric by transfer have not been successful in producing results which would compare favorably with the results produced by the direct textile printing methods. Aside from other technical considerations this has been due principally to the relatively high costs of manufacture of such dye transfer sheets and to the relatively slow and imperfect transfer methods used in making the transfer, which made it altogether impossible to use dye transfer sheets profitably for a regular and large commercial production in textile converting.

The use of dye transfer sheets for printing and dyeing multi-colored designs on fabrics also has some very valuable advantages over direct textile printing methods. For instance, in attempts to print fine multi-color half-tone designs by direct textile printing on fabrics, including the use of photomechanical reproduction methods, the woven fabrics present a multitude of interrupted multi-planar surfaces and the half-tone design a plurality of dot printing surfaces, which prevent continuous tone gradation of the directly applied half-tone printing on the irregular surface. On the other hand, the production of such multi-color half-tone designs in a perfect continuous tone gradation where even the screen dots of the printing surface become invisible can be effected without difficulty on the same fabrics through the intermediary of transferring such designs to a planar surface dye transfer sheet and then to the fabrics, the dye transfer sheet, having been previously printed with suitable dye inks in a high speed multi-color printing press.

Another advantage included in the use of dye transfer sheets is the better register of the different colors constituting the design, which can be produced on such a sheet, as compared to the register obtained in printing directly on such stretchable materials as fabrics. This fact is of special importance in the printing of photograph-

ically reproduced designs because each color repeats practically all its outlines, so that even relatively small differences in registry caused by stretching, for example, may spoil the final appearance of the design.

A further advantage of dye transfer printing on fabrics, is that dye transfer sheets may be stored without loss of their working qualities for a considerable time, so that the more expensive fabric material may be converted only when desired and is not spoiled if the printed design is not a commercial success.

It is the principal object of this invention to provide a low cost manufacturing process for the printing and dyeing of fabrics and other suitable absorbent materials by transfer, which involves the manufacture of dye transfer sheets carrying single or multi-color full-tone or half-tone designs, by high speed printing, and further to provide a transfer method and a transfer apparatus which permits perfect printing or dyeing of the fabric from the transfer sheet and at a relatively high speed, making it thereby possible to use dye transfer sheets profitably for the converting of fabrics even on a commercial scale.

Another and important object of the invention, includes the use of three or four standard primary dye colors, such as, yellow, red, blue or black which are superimposed on one another on the dye transfer sheet and after being applied to the transfer sheet, include in desired relation, continuous tone gradation through the whole range of possible color combinations, after which the transfer sheet may be transferred to the fabric finally reproducing the color scheme of the original design.

A further object of the invention is to provide a quick drying, thermo-plastic ink which is particularly suitable for high speed production transfer sheets and suited to transfer on fabrics.

Further objects and advantages of the invention will appear from the following disclosure thereof taken in connection with the attached drawings which illustrate diagrammatically apparatus for practising the invention and in which:

Figure 1 is a schematic section of a transfer sheet producing machine;

Figure 2 is a diagrammatic view of a printing machine for transferring the multi-color designs from the transfer sheet to the fabric;

Figure 3 is a partial plan view of a transfer sheet with an applied design thereon, and,

Figures 4 and 5 are diagrammatic views similar to Figure 2 showing other forms of printing

press arrangements on which the invention can be carried out.

Commercial printing and dyeing of fabrics, for example, woven silk requires the handling of the fabrics in a continuous manner, so that the entire roll or web of fabric, which may be 60 yards or more in length, may be treated in one operation. The continuous treatment must be economical, of great accuracy, and must insure the faithful reproduction of the design in outline and color. It is obvious that a dye transfer sheet suitable for such a process must also be produced in a continuous manner, i. e., by a continuous printing process which permits of printing multi-color design on a web in one operation and which produces rolls of dye transfer sheet in lengths corresponding to the lengths of cloth to be dyed.

As the most practical printing process for the manufacture of such dye transfer sheets, I prefer the rotogravure printing process, although I am not limited to this printing method. Rotogravure printing permits the use of quick drying dye inks and can be adapted to continuous multi-color printing on a web of transfer material in one operation. Another important point which makes rotogravure printing eminently suitable for this process, is the relative low costs to prepare the intaglio etched color printing cylinders by the usual photomechanical reproduction methods.

In practising the invention and to produce my special dye transfer sheets I make use of a rotogravure printing press as partly shown in Figure 1 having at least three but preferably up to six color printing units. Although the mechanical principles involved in this press are practically the same as those used in ordinary paper printing the printing itself is carried out differently and with special dye inks.

In ordinary paper printing the printing process furnishes a final product so far as the printed color layer of the design formation is concerned. In building up this color layer nothing else aside from the register of the colors need be considered, as the printed and superimposed colors by 45 translucency give a combined effect which very closely approaches the color of the original design. A very thin layer of ink, which generally is in greater part absorbed by the paper, is sufficient to build up the final design. Even at a 50 relatively high speed the correct superimposition of several colors printed consecutively in one operation causes little trouble under those conditions.

A dye transfer sheet, however, constitutes only 55 an intermediate product. The effect produced by the printed dye layer on the paper itself, is only of secondary interest. In my invention, all consideration must be directed to the potential properties of the dye layer for printing on the cloth, for instance, that this dye layer will be permanently soluble and be transferable to the fabric; that it be capable of producing the desired coloring, blending and other chemical effects on the fibres of the fabrics to which it will be applied 65 and that it will not deteriorate during storage, etc.

The long practice of textile printing has established certain commercial standards about 70 strength, brilliancy and fastness of color shades of printed fabrics and, therefore, merchandise produced by transfer methods must not be inferior to directly printed fabrics in this respect. Although it is relatively easy to produce dye transfer sheets which will produce some kind of coloring effects on fabrics, it has been rather diffi-

cult to produce dye transfer sheets which will give results equivalent or superior to those by direct printing on the fabrics.

In my experiments I have found that in order to produce by transfer such durable, intense and brilliant color shades on fabrics, it is necessary to produce a dye transfer sheet which carries (as compared to ordinary paper printing, a relatively heavy and permanently soluble layer of suitable dyes preferably in combination with an adhesive and thermoplastic binder material on its outer surface, and that is necessary to prevent the absorption of this dye layer by the supporting paper or other material.

In a copending application of Alfred B. Pöschel, Serial No. 560,245, filed August 29, 1931, a transfer sheet for general application has been described and among other things, the particular properties include a rubber-casein-formaldehyde composition coating applied previous to the printing operation to a supporting backing, preferably consisting of paper, to form an impermeable resilient somewhat tacky and thermo adhesive surface layer which is particularly advantageous to receive and give up the applied dyes. I have found that the same rubber casein formaldehyde composition is also particularly suitable for the production of dye transfer sheets by high speed printing and that it produces excellent results in transferring or applying the printed dyes to the fabrics at a relatively high speed.

Although I prefer to use this material as the most effective transfer medium in pursuance of this invention, I wish it to be understood that I am not limited to its use, because it is possible by 35 use of my special dye inks to produce on ordinary sized or otherwise coated paper, or similar materials, dye transfer sheets which will give fair transfer results in such cases where a cheaper grade of merchandise such as cotton, is processed 40 and where the greater refinement of the finished article is of less importance.

The transfer sheet must of necessity be pliable so that it can be impressed into the fabric throughout the multiplanar surface and thus dye both the 45 crest and valleys of the weave and on the other hand, it should not stretch unduly. On a dye transfer sheet, the correct printing and superimposition of each single color is particularly important, because the least faulty printing or imperfect superimposition of each color will change 50 the final color scheme of the design entirely and, consequently, the material which is dyed with imperfect transfer sheets will be out of shade and thereby be wasted.

In a high speed continuous multi-color printing on a relatively non-absorbent paper where each single color is consecutively overprinted or superimposed, the perfect superimposition of each color without running together of the colors is 60 difficult to obtain, and with increasing speed and required heavy body of ink, the correct superimposition, which cannot be dispensed with, becomes a decided problem.

In my experience I have found that in high 65 speed continuous multi-color printing of dye transfer sheets a correct superimposition of the solid color portions as well as of the half-tones of the single colors is only possible unless substantially instantaneously drying dye inks are used. 70 I have found that such instantaneously drying dye inks which give a very satisfactory result at a printing speed of 240 ft. or even more per minute, can best be prepared by using miscible liquids 75 which are suitable as solvents or vehicles of dyes

and which have a combined boiling point of about 65° C. at normal air pressure. The drying of such an ink, that means its change, from a liquid to a solid or semi-solid state is accomplished by the rapid evaporation of its liquid constituents, which can further be accelerated by airblowers and exhausters included in the construction of the printing press.

Suitable solvents or solvent combinations for the preparation of such inks are acetone-methyl alcohol, ethyl ether-methyl alcohol, methyl acetate-methyl alcohol, petroleum ether-acetone, etc.

I have found further that for the building up of a desirable body of dye layer on the transfer sheet it is of advantage to include in such a dye ink a viscous binding material. Such a binder material in order to facilitate the transfer process, which will be explained further below, should preferably possess adhesive and thermoplastic properties. It is obvious that such a binding material must also be permanently soluble (preferably in the same solvent as the dyes used). Further it should be colorless and should not prevent the rapid evaporation of the volatile constituents of the dye inks, and it should set quickly and not remain tacky or runny so that the perfect superimposing of each dye is insured and the safe handling of the finished transfer sheets at a later stage is possible.

One particular binding material which I prefer and which incorporates these properties is vinylite resin "A" manufactured by the Carbide and Carbon Chemical Corporation, the exact constituents of which are unknown to me.

To further improve the general qualities of these dye inks I prefer to include minor quantities of material which act as lubricants, (castor oil or the like), as neutralizing agent (sodium hydroxide or the like), and as plasticizers (di-butyl-phthalate) or the like.

Any material or condition that would tend to prematurely fix the printed dyes on the dye transfer sheet must be avoided. In actually preparing these dye inks I prefer to form inks which are true solutions, although it is possible to form suitable inks for the process which are suspensions.

Generally and in accordance with the three color reproduction practice which is followed in making each color by the usual photomechanical means of intaglio etched printing cylinders, it is only necessary to use three primary colors, yellow, red and blue for the printing of the transfer sheet. However, in some cases depending on the nature of the design a true black as a fourth color is of advantage to be included.

If a design in addition to its ornamental color arrangements calls for a unicolored bottom shade of which in most cases several different shades are required, I prefer to make a special printing cylinder for this bottom color and to print it directly on the fabric as an additional fourth or fifth color, instead of producing it by superimposition of the primary colors. The matching and changing of such bottom shades can in this way be accomplished without disturbing the harmony of the ornamental color arrangements. If the ornamental design itself is desired in different shades the primary colors, yellow, red, blue and black may be in whole or in part replaced by other colors.

It is also possible to produce transfer sheets which in addition to the regular dye printing have metallic inks like gold or silver or other pigments applied and which can be transferred satisfac-

tarily and simultaneously with the dyes, although these inks will produce only a surface effect without actual dyeing of the fabrics.

In the preparation of suitable dye stuff inks for my high speed printing process, basic dyes, acid dyes and substantive dyes are most suitable, the proper choice of which depends on the type of fabrics to be treated. The binding material and other constituents included in such dye inks may also be varied and may consist in whole or in part of cellulose derivatives, gums, carbohydrates like sucrose and similar materials in connection with sufficiently volatile solvent liquids.

As a specific example and not by any means intended to limit the invention, the following formulas of dye stuff inks are set forth. They have been used and found very suitable in the present process of high speed printing of dye transfer sheets for dyeing silk goods. These inks are concentrated and may be diluted.

Yellow:

300 cc. methyl alcohol	25
200 cc. acetone	
150 grams vinylite resin A	
150 grams rapidogen, yellow D	
10 cc. dibutyl phthalate	
10 cc. castor oil	
10 cc. lye solution	

Red:

200 cc. methyl alcohol	30
200 cc. acetone	
150 grams vinylite resin A	
100 grams rapidogen, red B	
10 cc. dibutyl phthalate	
10 cc. castor oil	
10 cc. lye solution	

Blue:

200 cc. methyl alcohol	40
300 cc. acetone	
150 grams vinylite resin A	
100 grams rapidogen, blue B	
10 cc. dibutyl phthalate	
10 cc. castor oil	
5 cc. lye solvent	

Black:

200 cc. methyl alcohol	50
200 cc. acetone	
150 grams vinylite resin A	
150 grams rapidogen, black	
10 cc. dibutyl phthalate	
10 cc. castor oil	
10 cc. lye solution	

Note.—Rapidogen dyes; the exact formula of which is unknown to me are sold by the General Dye Stuff Corp., in New York.

The specific dyes used in the formulæ of the application are:

Blue—Di and triphenylmethane coloring matters as Victoria blue B No. 729 Color Index number.

Red—Xanthene coloring matters as Rhodamine No. 749 Color Index number.

Yellow—Ketonimine coloring matters as Aurora mine G No. 656 Color Index number.

Black—Acridine coloring matters as Phosphine No. 793 Color Index number.

Dye inks prepared according to the above formulas form true solutions. The use of dye inks forming true solutions, involves in high speed printing dye transfer sheets a particular advantage, which is beneficial in producing binary

color shades as green, orange, or purple on the fabric.

The consecutive superimposing of one primary color over another in the rapid printing of the transfer sheet effects an inter-penetration of the superposed dyes due to the temporary solvent action of the superimposed dye ink on the underlaying one. Consequently binary colors as green, orange, purple are produced during the printing directly on the dye transfer sheet, and are not merely the effect of translucency as in ordinary rotogravure printing. I have found that this inter-penetration of the printed dyes permits the production of uniform and brilliant binary or blended color shades on the fabrics, and that it improves the transfer results inasmuch as in the final transfer step, less solvent and less time is required to bring about the perfect interpenetration or blending of the dyes on the fabric, in consequence of which a better linear sharpness of the design can be maintained and running and bleeding of the colors prevented.

The preparation of the printing cylinders as well as the actual printing operation do not need to be here further explained because they do not differ in principles from the ordinary reproduction and printing practice as used for example in rotogravure printing.

As illustrated diagrammatically in Fig. 1, suitable transfer paper 12 which is preferably coated, is conducted from a roll 11, over the successive printing cylinders 10 where the various dye inks such as yellow, red, blue and black are successively printed and superimposed in the desired registry. The finished printed transfer sheet 20 may be stored for a considerable length of time without deterioration, a period of one and one half years having shown no noticeable difference which permits the manufacture of the dye transfers independently of the time and locality of the ultimate use.

The transfer of the colors from the transfer film to the fabric is preferably made in an automatic machine such as diagrammatically shown in Fig. 2, in which the roll 13 carries the transfer film and the roll 14 carries the roll or web of fabric to be processed. This roll or web may consist of one continuous piece or previously joined pieces of the standard sixty yard pieces of woven silk. These pieces may be joined in any desired manner such as by adhesive paper thus avoiding wrinkles and preventing an appreciable loss of the material. The fabric to be printed and the transfer web then pass over suitable rollers to the heavy and simultaneously rotating calender rollers 26 which preferably include an adjustable pressure control not shown and which may be provided with suitable heating devices under thermostatic control. The heating element is indicated at 26a although either or both calender rollers may be heated. For effective operation a temperature of approximately 200° F. is found suitable.

The pressure on such rollers may be in the order of 100 pounds per linear inch and a single pair of rollers having approximately eight inches diameter have been found to be effective. These calender rollers temporarily join or mold the fabric and the transfer sheet into an intimate and processed contact which is made possible under the influence of heat and pressure by the adhesive and thermoplastic dye inks and/or thermo adhesive paper coating when such is used in making the dye transfer sheets.

If desired, suitable dust removers 27 may be

used to remove the dust, loose threads, etc., from the fabric and preferably a pair of adjustable rollers 127 are used for straightening the silk and preventing wrinkles. In the transfer film path a roller 128 is used as a tensioning device if desired.

The adjustable nozzles 129 may be laterally movable for spraying an atomized or vaporized solvent to preliminarily moisten the fabric or the transfer sheet or both where fabrics to be treated are too thick to be moistened from the reverse side by solvents. They may be used in addition to the solvent applying device hereafter to be discussed with thick fabrics, although they may be eliminated where thin silk or cotton fabrics are treated.

The combined fabric and transfer film 20-22 now passes over additional tensioning rollers 128 to the further calender units including the calender rollers 132 and 232. The lower calender roller may preferably have a flexible web 33 on it which in turn passes around a tensioning roller 35. The flexible web 33 which may be of felt, rubber or other similar pliant material is especially desired in order to make possible the impression of the weave in the fabric in the transfer film so that the depth of the weave may be equally as well dyed as the crest or surface of the weave. It is of course to be understood that the calender rollers instead of carrying this web may be backed with papier-mâché, felt or the like. At the first calender unit 32 the combined transfer web and fabric 20-22 meet the solvent carrying web 34 which is carried on the roll 134. The solvent carrying web 34 is of any suitable material such as cotton or other absorbent material which passes over suitable tensioning roller 37 and over the solvent feed roller 38 in the solvent tank 39. Other tension rollers 40 hold the absorbent material 34 in contact with the feed roller to suitably absorb the solvent in the tank. The doctor roller 41 controls the amount of solvent.

The use of an absorbent material as the carrier of the solvent has the advantage that a very complete distribution of the solvents within such material takes place before it enters in contact with the fabric, which in turn results in a very uniform distribution of solvents in the fabrics and consequently effects a uniform transferring and dyeing. The amount of solvents needed to bring about a satisfactory transfer necessarily varies with the type of fabrics to be processed, and it varies also with the degree of solubility of the dyes and the time of contact, and should be determined by a test. A surplus of solvent will cause blurred outline of design and insufficient solvent will cause a poor transfer or insufficient penetration.

One example illustrating the operation of this absorbent material is demonstrated by the fact that ordinary news print paper if saturated up to about 100% of its own weight permits the satisfactory processing of about 60 square yards of crepe silk per gallon of solvent. The particular solvent tried which gave excellent results on silk in accordance with the transfer sheet printed with dye inks as previously discussed consists of approximately 103 ounces of denatured alcohol (97%), 12½ ounces of acetic acid, and 12½ ounces of distilled water per gallon. It is of course necessary to vary the solvent action in correlation with the specific dyes, binders and other materials contained in the dye inks which are used in printing the transfer

sheets. Solvent mixtures are also preferred, although single solvents such as ethyl alcohol are sometimes sufficient. The mixtures must be able to dissolve the printed dyes quickly and should 5 preferably be capable of releasing the full tinctorial capacity of the dyes. Such solvents may also include materials which are chemically active in fixing the dyes within the fibers of the fabric. For example, alcohols, esters, ketones, 10 ethers, hydrocarbons, chlorocompounds, water, acetic acid, lactic acid, formic acid, diluted sulphuric acid, oil emulsions, ammonia, formaldehyde, bast soap, Glauber salt solution, tartar emetic, or other suitable chemicals may be used.

15 The first calender unit therefore presses together a transfer web 20 on one side and a solvent carrying web 34 on the opposite side against a fabric to be treated 22 in the center. As before mentioned this takes place under a suitable 20 pressure and preferably under a temperature of approximately 200° F. The heat for the calender may be introduced through suitable jets 36 which may be gas, steam, or otherwise.

The transferring and dyeing is the combined 25 effect of the chemical and physical interaction of solvents, dyes and fibers in connection with pressure and heat and a minimum of time is sufficient to bring about a satisfactory effect. While one transfer calender 32 will effect a satisfactory 30 transfer at a moderate speed of about 10 yards a minute, it is of advantage to use two or more transfer units so that the speed may be raised as high as 30 yards or more per minute. In such case it may be necessary to apply 35 additional solvent to the absorbent web such as by the spray nozzles 43 and 44. It is also obvious that instead of atomized liquids, hot vapors or boiling solvents may be blown from such nozzle. A hood 45 is preferably used to withdraw the vapors over the calender rollers 40 caused by either the spray or the vaporization of the solvents by the heat in order to improve working conditions and to recover the solvents if desired.

45 The processed fabric 22 after passing through the calenders is stripped from the solvent web 34 and the used transfer film 20, the transfer film and the solvent web being rerolled immediately for further use, and the processed fabric 50 may pass into a steam bath or other suitable treating step 46. A suitable blower 47 may be used to facilitate drying and after the fabric is suitably treated it will be rerolled on the final roll 48 for such use as may be desired.

55 Fabrics printed and dyed by this transfer process will have all of the qualities of ordinary printed fabrics in regard to strength, brilliancy and fastness of color, and in addition they will possess a superior and refined tone gradation which cannot be produced by regular textile printing methods.

A modified form of construction is shown in Fig. 4, in which the film 20 and fabric 22 pass between suitable pressure rolls 40 with a dry web 50 on one side of the fabric 22 and the transfer film on the opposite side. In this case the solvent carried in the tank 51 is applied by suitable rolls 52 which operate directly on the fabric itself. The upper rolls 53 are merely for the purpose of holding the fabric in contact with the solvent applying rolls 54 of which there may be one or more, depending on the amount of solvent to be applied.

In this construction the fabric transfer film and 75 web 50 pass around several rollers which are simi-

larly held under suitable pressure to bring about the transfer, and after transfer is completed the separate webs are separated and wound on the separate rolls. Doctor blades 54 may be used to prevent clogging of the rolls and in particular the web 50 prevents a smudging of the rolls due to the penetration of the dye inks into the fabric.

Another slightly modified form of construction is shown in Fig. 5, in which the film 20 and fabric 22 first pass over a roller 60 and then through 10 calender rolls 26 which may be heated through the pipe 36. This causes a preliminary and firm contact between the fabric and transfer film which may be preferred. The preliminary contacted fabric and film then pass through a suitable 15 moistening element 61 having solvent applying rolls 62 and pressure rolls 63 which hold the fabric film onto the solvent applying rolls.

A smudge preventing fabric 34 as previously described then is brought into contact with the 20 moistened fabric and transfer film as it passes through the calenders 32 which as previously described may be heated if desired. Subsequently to passing through the calenders the film 20 is 25 rerolled on the fabric roll 20a while the fabric 22 which has been processed is rerolled on the roll 22a or passed into any further treatment chamber. The cleaning fabric 34 is similarly rewound on the roll 34a.

It is to be understood that the factors of time, 30 pressure, quality and quantity of solvent and dye inks are important. The time factor may be changed by the addition of calender units, but the time is relatively short as suitable transfers have been made at a rate as high as 30 yards 35 per minute on crepe silk. The pressure on the rolls will vary in accordance with the thickness of the fabric and pressure of 75 to 100 pounds per linear inch corresponding to a thin crepe silk when the dyestuffs as heretofore disclosed 40 have been used, and the transfer has taken place in the presence of the preferred solvents. It is, of course understood that other modifications may be made in the application of the solvent and the arrangement of the apparatus disclosed is 45 intended to be only of a diagrammatic nature which will vary in accordance with the apparatus available although it represents the apparatus successfully tested. I therefore do not wish to be limited to the precise construction or methods 50 disclosed, but desire a broad interpretation of the invention within the scope and spirit of the disclosure herein and of the claims appended hereinafter.

I claim:

1. The method of producing printed and dyed multi-color designs on a textile fabric by transfer which comprises imposing and superimposing and inter-penetrating by high speed continuous multi-color printing, a plurality of primary dye colors 60 to produce a permanently transferable soluble dye layer, forming full-tone and half-tone designs on a relatively non-absorbent and resilient transfer sheet, joining said fabric and said transfer sheet in a temporarily persistent and intimate 65 contact, exposing the joined materials to a precisely regulated and timed simultaneous action of pressure and solvent at a high speed thereby dyeing and permanently fixing said dye colors in said fabrics and finally separating the dyed fabric 70 from the used transfer sheet.

2. The method of multi-color printing on textile fabrics which comprises superimposing multi-color soluble printed designs on a flexible, non-stretchable support, passing said support with the 75

- 5 multi-color soluble designs thereon in continuous contact with the textile fabric through a solvent applying means, applying sufficient solvent to transfer the multi-color designs from the transfer paper to the fabric without causing bleeding or running of the colors, applying pressure to effect the transfer and separating the paper from the fabric and fixing the color in the fabric.
- 10 3. The method of transferring unblended and blended colors to a fabric to be decorated and dyed which comprises the initial application of a plurality of separate and independent unblended dye colors on a relatively non-absorbent transfer sheet by high speed printing process, the solvent and vehicle of each dye color being the same by a rapid consecutive imposition and superimposition of the unblended colors on the superimposed parts of the printed design causing an inter-penetration and actual blending of said
